UNITED STATES PATENT OFFICE.

ERNEST HEDENSKOOG, OF MUSKEGON, MICHIGAN.

BALL-RACK.

1,324,116.

Specification of Letters Patent.

Patented Dec. 9, 1919.

Application filed February 27, 1919. Serial No. 279,546.

To all whom it may concern:

Be it known that I, ERNEST HEDENSKOOG, a citizen of the United States, residing in Muskegon, in the county of Muskegon and 5 State of Michigan, have invented a new and useful Improvement in Ball-Racks, of which the following is a specification.

This invention relates in general to ball racks and has more particular reference to 10 ball racks provided for use in connection with pocket billiard tables and the like.

Prior to my invention it has been frequently the custom in playing pocket billiards and other games of like character to 15 remove the balls of the several players from the pockets of the billiard table and place them in a rack formed of a plurality of horizontal shelves for the purpose of scoring, each player selecting a shelf and placing 20 thereon the balls pocketed by him. The use of such a rack as this requires that when the balls are to be replaced on the table they be lifted out singly and in twos and threes by an attendant or by the players and either 25 carried to the table and deposited in a racking triangle or requires them to be deposited in a basket or other receptacle as they are taken thus from the shelves. Either operation consumes considerable time and materially 30 delays the play.

It is a principal object of this invention to provide a commercial and practical ball rack from which the balls of the several players may be quickly discharged into a 35 basket or other receptacle for replacement on the table. I am aware that numerous attempts have been made to construct racks that will automatically deliver the balls but these have proven impractical in use and to 40 be the cause of considerable annoyance and expense to such an extent that practically the only ball rack in use today is the simple shelf rack earlier described. In some instances these automatic racks have required 45 that the balls fall considerable distances, ultimately damaging them; and in others the arrangement has been such that the discharging of the balls has required the provision of such complicated and easily dis- 50 arranged relatively moving parts that they are expensive to construct and operate and their periods of use short. By reason of the fact that devices of this character are usually used in public billiard rooms where

they are subject to rough usage and considerable abuse, it is necessary in a commercially practical device that they consist of few, simple and readily operated parts.

Principal objects of this invention are—to provide a ball rack of the simplest possible construction, which may be quickly and easily operated (operation being to merely place a basket in suitable position and press a button); to provide a ball rack which will quickly deliver the balls without 60 damage to them; to provide a rack which will not permit the accumulation of dust or dirt and which will therefore not require cleaning; to provide a rack of unusually sturdy construction and capable of being 65 operated by any unskilled attendant or player without the necessity of providing special instructions or directions for the purpose.

Numerous other objects and advantages 75 of the invention will be apparent as it is better understood from the following description when considered in connection with the accompanying drawing illustrating a preferred embodiment thereof.

On the drawing,

Figure 1 is a front elevation of a ball rack embodying my present invention;

Fig. 2 is a substantially vertical sectional view from front to back of Fig. 1;

Fig. 3 is an enlarged partial sectional view of a ball rack showing certain details of construction; and

Fig. 4 is a section on the line 4—4 of Fig. 3.

For the purpose of illustrating my invention I have shown on the drawing a rack in which it is embodied. This rack comprises a casing consisting of a suitably constructed head or top 11, vertical central rails 12, end rails 13, an inclosed lower portion 14 and a lower basket supporting shelf 15. The rails 12 and 13 are secured at their tops to a suitable member 16 of the head. The rails 13 extend all the way from the member 16 down to the shelf 15 and to them this shelf is fastened. The rails 12 are fastened at their front to the front member of the lower portion 14 and at their rear to a cross piece 17. The rails 12 and 13 provide spaces between them to receive the balls in gravity columns, as indicated in dotted lines in Fig. 2. The rails 12 and 13 are provided with

longitudinally extending grooves 18 to hold the balls in the columns and these grooves are preferably inclined slightly up and back from the bottom so that the balls resting 5 between the rails are held by gravity against the back part of the grooves. This inclination may be obtained by inclining the rails 12 as shown and inclining also the outer edge of the rails 13. A support 19 is positioned 10 normally beneath the spaces for receiving the balls and this support in the present instance consists of a bar guided at its ends 20 in the rails 13. This bar or support may be moved back horizontally to retract it from 15 beneath the balls, this movement being accomplished by means of a push button 21 upon the end of a sleeve 22 having a bearing in the front wall of part 14. The inner end of this sleeve 22 is clamped between the 20 support 19 and a fastening strap 33. A rod 34 fixed at its rear end in a bracket 35 extends forwardly and into the sleeve 22 for which it forms a rear bearing. The sleeve bears against the forward edge of the ball 25 support 19 and when the push button is pushed inwardly the sleeve pushes the support from beneath the columns of balls. A spring 36 is disposed between the bracket and the support 19. This spring returns the 30 parts to normal position after each discharge, this return movement being halted by a second stop or sleeve 37 about sleeve 22 and engaging the front wall of part 14 and the support. Washers 48 may be provided 35 to take the thrust of the spring on the support 19 and the front wall of part 14, if desired.

A basket (generally indicated at 24) may be placed upon the shelf 15 and in order 40 that this basket may be closely beneath the guiding part 14 which guides the balls into it upon release, the front and back guiding parts are cut away at 25 to receive the handle 26 of the basket. The sleeve 22 is preferably 45 located immediately above these cut-away parts and the rails 12 are arranged so that one of them is above the handle and also above the sleeve to prevent balls dropping out of the gravity columns upon release 50 from hitting either the rod or the basket handle. The sleeve and basket handle are of course preferably located centrally and this arrangement can be obtained by providing an odd number of the rails 12 giving 55 to the rails 13 an even number of spaces for the balls.

Inclined guiding partitions or blocks 27 are provided at the sides to direct the balls from the end spaces into the basket and a 60 bar or cross brace 28 is located centrally between the front and back members of the guiding part, this cross brace being located at the upper part of the cut-away portions 25.

The push button 21 normally extends in 65 front of the front guiding member 14 and in order that it may not be inadvertently pressed or bent by persons leaning against it I provide two protecting blocks or members 29, one on each side. 70

The balls are inserted into the spaces between the rails from the front and in order to permit this and further insure the balls remaining in the channels, downwardly inclined grooves 31 are provided and spaced 75 apart distances equal to the diameter of the balls. These grooves or recesses 31 are preferably so located that when the balls are resting in the channels the larger diameters of the balls are located between the grooves 80 31 and thereby additionally held in place.

The operation of the device consists merely in inserting the balls as they are pocketed in the play and after each game removing them for reracking by positioning 85 the basket and pressing the button 21. This may be quickly accomplished by grasping the basket handle by the operator and as he places it upon the shelf pressing the button 21 with the thumb of the hand holding 90 the basket thus rendering the removing of the balls from the rack a single and quick operation.

I have very carefully provided means to prevent the balls falling out of the front of 95 the rack both when they are resting in the columns and when they are being delivered. The location of the recesses or grooves 31 is such that the balls are positioned back of the unrecessed front parts of the rails so that 100 there is no danger of them falling out while they are at rest. However in discharging, the balls move down and successively align with the recesses 31 and the pressure of the balls upon each other is prevented from 105 causing them to pass out from these recesses first by the inclination of the grooves 18 and second and also by the inclination of the recesses or grooves 31. There is thus no possibility of the balls falling out at the front 110 in the rack constructed in accordance with my invention.

The baskets ordinarily used to convey the balls from the racks to the table have relatively rough bottoms and in order that these 115 baskets may not wear or mar the shelf 15 as in use I may provide an anti-wearing and anti-marring surface upon the upper shelf face. This surface I prefer to provide by securing a thin veneer of compressed fiber 120 indicated at 32 on the drawing.

It is thought that the invention and many of its attendant advantages will be understood from the foregoing description, and it will be apparent that various changes may 125 be made in the form, construction and arrangement of the parts without departing from the spirit and scope of the invention.

or sacrificing all of its material advantages, the form hereinbefore described being merely a preferred embodiment thereof.

I claim:

5. 1. A rack for pocket billiard balls comprising a casing providing a plurality of upright inclined ball receiving channels for holding the balls in gravity columns.
10. 2. A rack for pocket billiard balls comprising a casing providing upwardly and rearwardly inclined channels for holding the balls in gravity columns and providing also downwardly and inwardly inclined channels opening into the first mentioned channels to permit insertion of the balls into said first mentioned channels.
15. 3. A rack for pocket billiard balls comprising in combination a casing having a series of upright members providing channels in which the balls are arrangeable in gravity columns, horizontally slideable supporting means for supporting said columns of balls, and means for directing the balls from all of the columns into a basket or other receptacle.
20. 4. A rack for pocket billiard balls comprising in combination a casing having a series of upright members providing channels in which the balls are arrangeable in gravity columns, horizontally slideable supporting means for supporting said columns of balls, and means for directing the balls from all of the columns into a basket or other receptacle, movement of said supporting
25. 5. A rack for pocket billiard balls comprising in combination a casing having a series of upright members providing channels in which the balls are arrangeable in gravity columns, horizontally slideable supporting means for supporting said columns of balls, and means for directing the balls from all the columns into a basket or other receptacle, means from normal position permitting immediate and simultaneous delivery of all the balls of all the columns.
30. 6. A rack for pocket billiard balls comprising in combination a casing having a series of upright members providing channels in which the balls are arrangeable in gravity columns, a common support for said columns of balls, and a manipulative device engageable by the operator for releasing all the balls in said columns simultaneously, said device being protected against inadvertent manipulation by casing parts.
35. 7. A rack for pocket billiard balls comprising in combination a casing having a series of upright members providing channels in which the balls are arrangeable in gravity columns, a common support for said columns of balls, and a manipulative device engageable by the operator for releasing all the balls in said columns simultaneously, said device extending through the front of the casing, and guards extending out on the casing front to protect the said device against inadvertent operation and damage.
40. 8. A rack for pocket billiard balls comprising in combination a casing having a series of upright members providing channels in which the balls are arrangeable in gravity columns, a horizontally reciprocating member beneath said channels for sup-

porting said columns, and a push button for moving said member from supporting position to permit discharge of all the balls in all the columns.

8. A rack for pocket billiard balls comprising in combination a casing having a series of upright members forming channels in which the balls are arrangeable in gravity columns, a horizontally reciprocating member beneath said channels for supporting said columns, a push button for moving said member from supporting position to permit discharge of all the balls in all the columns, and yielding means for returning said member to normal column supporting position.

9. A ball rack, comprising a casing providing a plurality of vertical spaces for receiving the balls in gravity columns, a support for a basket therebeneath, an inclosed guiding part for directing the balls out of the columns and into the basket, said inclosed part being interrupted centrally to accommodate the handle of the basket.

10. A ball rack, comprising a plurality of upright rails defining spaces for holding the balls in gravity columns, means for supporting said balls and releasing them to permit them to drop into a basket, and means for centering the basket with the handle beneath one of said rails to prevent the balls entering the basket from hitting the handle.

11. A ball rack, comprising a casing providing spaces for holding the balls in gravity column, a retractable support for the balls therebeneath, the bottom of said casing being open and adapted to direct the balls into a basket and an operating member for said retractable support operable by the hand of an operator moving the basket into position.

12. A rack for pocket billiard balls comprising in combination a casing having a series of upright members providing channels in which the balls are arrangeable in gravity columns, a retractable support beneath said columns and means for manipulating said support to release all the balls in said columns said means comprising a push member, and an elongated bearing therefor disposed within said push member.

13. A rack for pocket billiard balls comprising in combination a casing having a series of upright members providing channels in which the balls are arrangeable in gravity columns, a retractable support beneath said columns, and means for manipulating said support to release all the balls in said columns, said means comprising a pair of telescoping parts one movable and the other fixed, and a spring for moving the movable part back to normal position.

14. A rack for pocket billiard balls comprising in combination a casing having a series of upright members providing chan-

nels in which the balls are arrangeable in gravity columns, a retractable support beneath said columns, and means for manipulating said support to release all the balls in said columns, said means comprising a pair of telescoping parts one movable and the other fixed, and a spring for moving the movable part back to normal position, and a stop sleeve on the moving part for stopping movement of the support when it is returned to normal position.

15. A rack for pocket billiard balls comprising in combination a casing having a series of substantially upright members providing channels in which the balls are arrangeable in gravity columns, movable supporting means for sustaining all of said columns of balls, means for directing the balls from all of said columns into a receptacle when said supporting means is removed, and

means arranged substantially in line above the point of delivery of said directing means for operating said supporting means.

16. A rack for pocket billiard balls comprising in combination a casing having a series of substantially upright members providing channels in which the balls are arrangeable in gravity columns, movable supporting means for sustaining all of said columns of balls, means for directing the balls from all of said columns into a receptacle when said supporting means is removed, operating means arranged substantially in line above the point of delivery of said directing means for moving said supporting means to release the balls, and casing parts which protect said operating means against accidental actuation.

ERNEST HEDENSKOOG.
